COTTON FIBER ROLLING DEVICE

Filed April 6, 1931

UNITED STATES PATENT OFFICE

HARVEY P. CHANEY, OF LOS ANGELES, CALIFORNIA

COTTON FIBER ROLLING DEVICE

Application filed April 6, 1931. Serial No. 528,042.

This invention relates to a device for rolling cotton fiber into rolls suited for holding grease or lubricating oil in contact with bearings.

5 An object of the invention is to provide improved means for rolling loose cotton ravelings together in such a manner as to eliminate the necessity of tying relatively small rolls of cotton together, the device, instead forming a complete roll of cotton of the size desired to fill properly the bearings in which the cotton is to be used.

Another object of the invention is to provide a device of this kind which is provided 15 with improved means for adjusting the cotton handling elements in such a manner as to form cotton rolls of a desired length and diameter.

Other objects, advantages and features of 20 the invention may hereinafter appear.

Referring to the accompanying drawing which illustrates what is at present deemed to be a preferred embodiment of the invention,

25 Fig. 1 is a plan view of the complete device.

Fig. 2 is a side elevation thereof.

Fig. 3 is an end elevation thereof.

Referring in detail to the drawing, the 30 frame of the device comprises the base plate 5, an upstanding end plate 6 and an adjustable guide plate 7, the end plate 6 also serves as a guide plate, and may be formed in one piece with said base plate, but in the drawings is 35 shown as a separate plate which is secured to the base plate by means of an angle iron member 8, the horizontal flange 9 of said angle iron member underlying the edge portion of the base plate 5 and being riveted thereto, while the upstanding flange 10 engages the outer surface of the lower edge portion of the plate 6 and is likewise riveted thereto.

40 The adjustable guide plate 7 has secured to its outer or left hand face (as viewed in Fig. 3) the upstanding flange 11 of an angle iron member 12, the base flange 13 of said angle iron member being, by means of screws 15, 45 adjustably secured to the base plate 5. The

angle iron members 8 and 12 preferably extend the entire length of the base plate 5.

The upstanding plates 6 and 7 are maintained in parallel spaced relation to each other. The adjustable plate 7 is provided 55 with a bearing aperture 17 and the other up-right plate 6 is provided with a bearing box 18 of a ball bearing secured to the outer face of said plate 6. The preferred manner of securing said bearing box 18 is by means of 60 screws 19 which are screwed down upon a guard plate 20 provided at the opposite side of the plate 6 from the bearing box 18, said guard plate and the plate 6 being suitably apertured to permit this to be done.

Upon the bearing means provided by the bearing box 18 and a bearing 27 which is fixed to the plate 7, is mounted a cotton-winding spindle 25, said spindle having at one end a reduced extension 26 which extends 70 through the bearing opening 17 and rests upon the bearing. To the outer end of spindle 25 is secured, or formed integral therewith, a crank 30 which may be used if it is desired to operate the device manually.

75 The spindle 25 is shown as being square in cross section, said spindle having a tapered end portion 25a which, however, may blend from square to round near the end thereof. During the rotation of the spindle the operator maintains more or less pressure upon the crank tending to hold the spindle with the reduced end portion 26 thereof in engagement with the bearing 27. In Fig. 1 a roll of cotton 25c has its outline indicated by broken 80 lines.

85 The device is provided with a comb structure to cooperate with the spindle 25, said comb structure comprising a stationary cross bar 35 which is desirably square in cross section. This bar is supported in substantially parallel relation to the spindle 25, and desirably has at its end a screw threaded reduced portion 36 which is extended through the up-right plate 6 and which has a securing nut 90 37 screwed thereonto. The middle portion of said bar 35 extends through an aperture provided therefor in the other guide plate 7.

95 Teeth may be provided for the cross bar 35 of the comb by a variety of means, but said 100

teeth are shown as consisting of a plurality of screw bolts 40 which extend horizontally through the bar 35 and have a screw threaded connection therewith, said bolts being provided with lock nuts 41 to secure them in the adjusted position. These bolts have pointed end portions 42 which project toward and cooperate with the manually or otherwise operable spindle 25.

10 The base plate 5 is shown provided with two inner rows of apertures 50 and with a row of apertures 51 near each outer end of said plate, all of these apertures being properly spaced to receive the four attaching screw bolts 15 with which the adjustable guide plate 7 and its supporting angle iron member 12 are provided. Each of the outer rows of screw holes 51 is provided with a gauge 51a, the graduations of said gauge being so numbered 20 as to indicate the space between the guide plates 6 and 7 in the various adjusted positions of said guide plate, it being understood that this space coincides with the length of the roll of cotton waste being formed by the 25 device. The spindle 25 is made sufficiently long to permit the guide plate 7 to be moved as great a distance from the guide plate 6 as the width of the base plate 5 will permit.

As indicated by dotted lines at the left of the plate 7, the comb 35 is provided with additional threaded apertures or sockets adapted to receive more teeth like the bolts 41 which form teeth at the right side of said plate. Whenever the plate 7 is moved a greater distance from the plate 6 in order to provide for winding a longer roll of cotton upon the spindle 25, the required number of additional teeth are inserted in order to complete the comb structure between the plates 6 and 7.

In the operation of the device the mass of cotton ravelings are deposited within the space between the upright plates 6 and 7 at the side of the spindle opposite to the comb teeth formed by the bolts 40, and the operator with one hand feeds the cotton mass gradually forward toward the comb structure and spindle 25 while at the same time he rotates said spindle by the other hand by means of the crank 30. As the cotton passes across the pointed portions 42 of the comb teeth 40 the fibers thereof are combed out and are placed under a sufficient tension to insure that they will be wound upon the spindle 25 with the compactness desired. After a roll of waste cotton of the desired diameter has been accumulated upon the spindle, the operator will retract said spindle by sliding it outwardly until it is completely withdrawn from both the bearings, or at least until the tapered end portion of the spindle has been brought sufficiently close to the outer guide plate 6 to permit the cotton roll 25c to be removed. After the removal of this roll the spindle will 65 be restored to its normal position in order

that another roll of cotton may be formed thereon.

I claim:

1. In a device of the kind described, a base plate, a plurality of upstanding guide plates mounted thereon, a substantially horizontal comb mounted upon and supported by said plates, a rotatable spindle also supported by said guide plates, said spindle being in spaced substantially parallel relation to the teeth of said comb, and said guide plates being adapted to form a guideway along which cotton may be fed to said spindle. 70

2. In a device of the kind described, a base plate, a plurality of upstanding guide plates mounted thereon substantially parallel to each other and adjustable upon said base plate to vary the distance between them, a bearing mounted upon each of said guide plates, a rotatable fiber winding spindle supported by said bearings and in slidable relation to them, said spindle having a hand crank secured to one end thereof, and a comb mounted in a position to cooperate with said spindle, said guide plates being adapted to cooperate with said base plate to form a guideway for feeding fibers of cotton or the like to said spindle by one hand of the operator while he rotates said spindle with his other hand. 80

3. In a device of the kind described, a base plate, a pair of guide plates mounted upon and upstanding from said base plate, a fiber winding rotatable spindle supported by said guide plates, said guide plates having bearings for said spindle, said spindle being longitudinally slidale to retract the same from the space between said guide plates to release a roll of waste cotton accumulated thereon, and a comb device operatively related to said spindle. 100

4. In a device of the kind described, a base plate, a plurality of upstanding guides mounted thereon one of which is adjustable, a comb mounted upon and supported by said guides, a portion of said comb projecting beyond one of said guides in order to provide for supporting the comb when the guides are adjusted at a greater distance apart, and a spindle mounted in spaced substantially parallel relation to said comb, said guides being adapted to form a guideway along which a fibrous substance may be fed to the side of said spindle which is opposite to said comb. 110

5. In a device of the kind described, a base plate, a plurality of upstanding guide plates mounted thereon, one of which is adjustable, a comb mounted upon and supported by said guide plates, a portion of said comb having a slidale fit within one of said guide plates and projecting therebeyond, and a spindle mounted in spaced substantially parallel relation to said comb, said guide plates being adapted to form a guideway along which a 120

fibrous substance may be fed to the side of said spindle which is opposite to said comb, the aforementioned projecting portion of said comb having sockets adapted to receive removable teeth.

5. 6. In a device of the kind described, a plurality of upstanding guides mounted thereon one of which is adjustable, a comb mounted upon and supported by said guides, a portion of said comb having a slidable fit within one of said guides and projecting therebeyond, and a spindle mounted in spaced substantially parallel relation to said comb, said spindle being constructed and arranged to bridge the space between said guides when they are adjusted at different distances from each other, said guide plates being adapted to form a guideway along which a fibrous substance may be fed to the side of said 20 spindle which is opposite to said comb, the aforementioned projecting portion of said comb having sockets adapted to receive removable teeth.

In testimony whereof I hereunto affix my
25 signature.

HARVEY P. CHANEY.
